Patented Apr. 5, 1960

187,626

COMBINED SWIMMING FLOAT AND EXERCISER

James H. Irving, Los Angeles, Calif.

Application July 24, 1959, Serial No. 56,918

Term of patent 7 years

(Cl. D71—1)

Fig. 1

Fig. 2

Fig. 3

Fig. 1 is a side elevational view of a combined swimming float and exerciser showing my new design; Fig. 2 is a plan view; and

Fig. 3 is an end elevational view thereof, but on a larger scale.

I claim:

The ornamental design for a combined swimming float and exerciser, substantially as shown.
